FIG. 1 is a front elevation view of a face panel for a coin telephone box showing my new design with the box and its lower coin return and coin storage sections, and the telephone transmitter-receiver instrument and cord, shown in broken line outline;

FIG. 2 is a rear elevation view thereof;

FIG. 3 is a side elevation view thereof, the opposite side being a mirror image; and,

FIG. 4 is a bottom view thereof, the top being a mirror image.

The broken line showing of the telephone box, telephone transmitter-receiver instrument and cord, etc. is for illustrative purposes only and forms no part of the claimed design.
